F. L. GILMAN,
HEDGE TRIMMER.

APPLICATION FILED SEPT. 25, 1905. RENEWED MAR. 30, 1908.

902,529.

Patented Oct. 27, 1908.

UNITED STATES PATENT OFFICE.

FRANK LEANDER GILMAN, OF EUGENE, OREGON.

HEDGE-TRIMMER.

No. 902,529.

Specification of Letters Patent. Patented Oct. 27, 1908.

Application filed September 25, 1905, Serial No. 279,270. Renewed March 30, 1908. Serial No. 424,116.

To all whom it may concern:

Be it known that I, FRANK LEANDER GILMAN, a citizen of the United States, and a resident of Eugene, in the county of Lane and State of Oregon, have invented a new and Improved Hedge-Trimmer, of which the following is a full, clear, and exact description.

This invention relates to hedge-trimmers, and it consists substantially in the details of construction and combinations of parts hereinafter more particularly described and pointed out in the claims.

The invention has reference more especially to hedge-trimmers of the hand-operated type, and one of the principal objects thereof is to provide a structure of this kind of an embodiment to overcome numerous disadvantages and objections encountered in the use of many other structures of the kind hitherto devised.

A further object is to provide a hedge-trimmer which is simple in construction and comparatively inexpensive to manufacture, besides being thoroughly effective and reliable for its purposes, and possessing the capacity for long and repeated service.

The above and additional objects are attained by means substantially such as are illustrated in the accompanying drawings, in which

Figure 1 is a view in perspective, illustrating the manner in which my improved hedge-trimmer is fastened or attached to the body of the operator therefor; Fig. 2 is an enlarged side view of my improved hedge-trimmer, illustrating the construction and organization of the parts thereof more clearly; Fig. 3 is a still further enlarged side view (in part section), illustrating more clearly the means employed for effecting the raising and lowering of the support for the motion transmitting devices for the oscillatory blades or cutters of the trimming devices proper; and Fig. 4 is a transverse sectional view taken on the line 4--4 of Fig. 2.

Before proceeding with a more detailed description, it may be stated that in the form of my improvements herein shown I employ special means for attaching or fastening my improved hedge-trimmer to the body of the person operating the same, special means being also employed between said first-named means and the trimming devices proper of the structure, for supporting special motion-transmitting devices employed for operating

specially constructed oscillatory blades or cutters comprised in said trimming devices proper. Special means are also employed for altering the position of the motion-transmitting devices as occasion may require in the use of the structure, other special means being employed for enabling the structure to be held in one hand any desired distance from the body while the same is operated by the other hand, said means also enabling the trimming devices proper to be held in any desired position laterally of the hedge operated upon.

Still further special means are employed permitting the trimming devices proper to be adjusted and held at any desired angle of inclination, either upwardly or downwardly, relatively to the hedge being trimmed, the organization being such as to adapt the structure to the trimming of hedges both quickly and economically, as well as in accordance with any preferred style of trimming.

Reference being had to the drawings by the designating characters marked thereon, 1, 1 represent substantially semi-circular members of metal adapted to be fitted to one side of the body of the operator when using my improved hedge-trimmer, said members being provided at one end thereof with flexible strips 2, the free ends of which are adapted to be secured about the other side of the body of the operator by means of buckles 3 secured to the remaining ends of the said members 2. These members are held together a sufficient distance apart by means of a vertically disposed preferably metal strip 4, connecting the members at or near the ends thereof, lying against the front of the body of the operator, substantially as indicated in Fig. 1. Also connecting the members 2 substantially between the ends thereof is a vertically disposed plate 5, the lower end 6 of which is preferably enlarged and formed from the underside thereof with an outward bulge 7, thus to adapt the hip-bone of the operator to be partially received at said lower end of the plate 5, and thereby, in a measure, assisting in the support of the weight of the structure upon the body. If desired, also, a strap or suspending device 8 may be employed to lie over the shoulder of the operator, thus to relieve his body still further of the weight of the structure.

The plate 5 is secured to the members 2 by rivets 9, or in any other suitable way,

while secured to the outer face of said plate, preferably by means of rivets 10, are the ends of a segmental plate 11 provided with any desired number of holes or perforations 12 located suitable distances from each other, see more especially Fig. 3. Pivoted at 13 to the outer surface of the plate 5, is the rearward end of a forwardly disposed member 14, while pivoted at 15 to the forward end 10 of this member is an arm 16, the rearward end of which is formed at the edge thereof with a series of teeth 17 disposed on the arc of a circle, said teeth being adapted to be engaged by a pin 18 carried at the inner side of the forward end of a pawl 19 pivoted at 20 to the outer side of the said forwardly disposed member 14, said pin also being of length sufficient to enter any desired one of the holes 12 in the segmental plate 11 whenever the arm 16 may be adjusted relatively to the member 14, either up or down, in a manner to bring the space between any two of the said teeth 17 in registry with or before said desired one of the holes.

Rotatably supported by the said arm 16 in any suitable way, is a shaft 21, rigid with which is a toothed gear-wheel 22 of proper size or dimensions, said shaft having also rigid therewith at its outer end an operating crank 23 provided at its free end with a suitable handle 24. The teeth of this gear-wheel 22 engage with the teeth of a pinion 25 rigid with the outer end of a shaft 26, also rotatably supported by the member 16 at or near the free end thereof, the said shaft 26 having rigid therewith, on the inner side of the member 16, a balance wheel 27, and also having connected thereto at its inner end, in any suitable way, one end of a flexible shaft 28, the free end-portion 29 of which is rotatably received in a bearing 30 therefor supported by a flange 31 of an extension 32 of the back-plate 33, rigid with 45 which are the stationary blades or cutters 34 of the trimming devices proper for my improved structure.

The extremity of the said end portion 29 of the flexible shaft is provided with a disk 36 carrying a crank-pin 37, in movable connection with which is a pitman 38, the outer end of which is in movable connection at 39 with the reciprocating member 40 for oscillating the movable blades or cutters 41 of the trimming devices proper, each of which is pivoted at 42 relatively to the said stationary blades or cutters 34. It will thus be seen that by taking hold of the handle 24 of the crank 23 and turning the same to impart 60 rotary motion to the gear-wheel 22, similar motion will be communicated to the shaft 26 through the medium of the pinion 25, and consequently this motion will be transmitted through the medium of the flexible shaft 28 to the disk 36 and its crank-pin, thence to

the reciprocating member 40 of the trimming devices proper through the intermediary of the said pitman 38, it being understood that in this way the trimming devices proper are operated to trim a hedge.

The back-plate 40 of the trimming devices proper has an extension 43, to which is secured, by means of a pin or rivet 44, the member 45 of a bracket, the other member 46 of which has movably secured thereto, by means of a screw 47 and nut 48, the forward end or extremity of a tubular member 49 which is supported in a sleeve 50 in a manner to be both rotated and adjusted longitudinally therein, and held to either position 80 to which it may be set by means of a screw-pin 51 and nut 52, said pin being inserted through corresponding openings 53 therefor, with which may be made to register any desired ones of corresponding openings 53^a 85 formed in sets in the said tubular member 49, disposed out of alignment with each other at different portions of said tubular member. In this way this tubular member may be located in the sleeve to carry the trimming devices proper to any desired position laterally of the remaining elements of the structure, while due to the invariable connection between the forward end of the tubular member and the member 46 of the hereinbefore-mentioned bracket, it is apparent that the trimming devices proper may be tilted or inclined at any desired angle, either upwardly or downwardly relatively to the hedge being trimmed, and secured in such position by 100 simply tightening the nut 48 upon the screw 47. The sleeve 50 is mounted upon one end of a rod 54, preferably having a covering 55 of rubber or other soft or yieldable material, thus to constitute a hand-grip, while extending from the other end of said rod 54 at substantially right angles thereto, is one end of a plate 56, carrying at the other end thereof a suitable cuff or support 57 for the forearm of the operator, which cuff may be sometimes employed in the operations of hedge trimming, by which to brace and strengthen the arm of the operator while engaged with the structure in the trimming of a hedge.

From the foregoing it will be seen that my improved hedge-trimmer may be adapted to any of the requirements of such a structure, and it should be added that instead of altering the position of the motion-transmitting devices for the trimming devices proper by 11 adjusting the member 16 with reference to the forwardly disposed plate 14, it is apparent that similar adjustments may be effected by raising or lowering the said plate 14 on its pivot 13, and securing it in the desired position with reference to the body of the operator by means of the hereinbefore-mentioned pin 18, which is inserted in the proper one of the holes 12 in the segmental plate 11.

It will be understood that the hand-grip is manipulated with one hand, while the motion-transmitting devices are operated with the other.

5. It should be added that the pawl 19 is sprung against the side of the forwardly disposed plate 14, and that the latter has a hole or opening 58 therein which, in the adjustments of the plate, is made to register with the appropriate one of the holes or openings 12 in the segmental-plate 4, it being apparent that the pin 18 carried at the end of the pawl also extends through said hole 58, and to disengage which the pawl has to be pulled outwardly from the plate, again springing into place when released.

It should be further added that the oscillatory blades or cutters 41 of the trimming devices proper are in pivotal relation with the reciprocatory member 40, at 59, thus to be actuated therefrom in an obvious manner.

Having thus described my invention, I claim as new and desire to secure by Letters Patent:

25. 1. A hedge trimmer comprising a plurality of independent supports, trimming mechanism upon one of said supports, said support being provided with a hand grip, operating mechanism on the other support, means for attaching said support to the body of the operator, and a flexible shaft connecting the operating mechanism with the cutting mechanism.

35. 2. A hedge trimmer comprising a plurality of independent supports, a hand grip upon one of the supports, cutting mechanism adjustably connected with the support, means for connecting the other support to the body of the operator, operating means for the cutting mechanism connected with said last named support, and a flexible shaft connecting the operating means and the cutting mechanism.

45. 3. A hedge trimmer comprising a plurality of independent supports, means for connecting one of said supports to the body of the operator, an arm extending from said support, a second arm pivoted to the free end of the first arm and provided with rack teeth, a pawl on said first named arm for engaging the rack teeth, whereby to adjust said arm with respect to the first named arm, cutting mechanism connected to the other support, operating mechanism for said cutting mechanism upon the adjustable arm of the first named support, and a flexible shaft connecting the operating mechanism and the cutting mechanism.

55. 4. A hedge trimmer, comprising a plurality of independent supports, cutting mechan-

ism connected with one of said supports, means for attaching the other of said supports to the body of the operator, an arm extending from said last named support, means for varying the position of the arm 65 with respect to the support, operating means for the cutting mechanism supported by said arm, and a flexible shaft connecting the operating means and the cutting mechanism.

5. A hedge-trimmer, comprising means for 70 attaching the same to the body of the operator, trimming-devices proper, motion-transmitting devices therefor, and a support for said last-named devices, embodying a forwardly disposed plate pivoted to a part of 75 said means, a segmental-plate secured to said part and having openings therein, the plate first-named having an opening therein for registry with either of said openings in the segmental plate, and a member pivoted to 80 said first-named plate, and having at the inner end thereof a series of teeth disposed on the arc of a circle, said forwardly disposed plate being provided with a spring pawl carrying a pin, as and for the purpose set forth. 85

6. A hedge trimmer, comprising a plurality of independent supports, trimming devices connected with one of said supports, means for attaching the other of said supports to the body of the operator, an arm adjustably connected with the last named support, means for operating the trimming devices connected with said arm, said means comprising a gear wheel, a crank rigid with the shaft thereof, a pinion driven by said 95 wheel, a flexible shaft having one end thereof connected with the shaft of the pinion, and its other end rotatably mounted on a stationary part of the trimming devices, and a crank and pitman connecting said shaft with 100 the movable elements of the trimming device.

7. A hedge-trimmer, comprising trimming devices proper, having an extension from a stationary part thereof, a bracket secured to the extension, a bar having its forward end 105 adjustably connected to the bracket, a hand-grip, a member carried thereby, in which the bar is supported, the latter being adapted to be turned and moved longitudinally in said member, and a plate extending from said 110 hand-grip, provided with a cuff for the reception of one of the forearms of the operator.

In testimony whereof I have signed my name to this specification in the presence of 115 two subscribing witnesses.
